SPRING MEANS FOR ROLLER MILLS
AND THE LIKE

Joe Crites, Larchmont, N. Y., assignor to Combustion Engineering-Superheater, Inc., New York, N. Y., a corporation of Delaware

Application November 17, 1949, Serial No. 127,980

3 Claims. (Cl. 241—133)

1

This invention relates to roller mills and the like, and particularly to improved means for maintaining desirable pressures upon the material being ground between the rolls and the grinding member (ring, bowl, table or the like) in such mills.

Heretofore, in mills of the so called "roller" type here considered, the pressure on the material has been produced by means employing a single spring acting to force each roll against the grinding member, the pressure being varied by varying the compression of the spring.

Preferred spring means should provide the proper pressure on each material of a different grindability being ground under the roll and at a suitable predetermined gap between the roll and the grinding member (illustratively referred to hereinafter as "ring" or "bowl"). However said pressure should not become excessive when the gap is materially increased by the passage therethrough of foreign matter, such as tramp iron. Furthermore said spring means should preferably provide a relatively low pressure on the roll when the roll is near the ring because then the roll will nip material, such as coal, with a rolling action instead of tending to plow it aside as is the case when the pressure is higher. Also the pressure on the roll should be low when the roll is near the ring to minimize noise and vibration; for with high spring pressure and a small gap between the roll and ring, there is no thick cushion of material to absorb the noise or vibration. But it is desirable to have the pressure build up rapidly as the material in the bowl accumulates to get quick response to changes in output; for example when the mill is used for firing steam boilers in power plants.

Heretofore the above mentioned preferred advantages have not been realized in roller mills when the pressures on the rolls were produced by means employing a single spring, and it is an object of this invention to provide improved spring means, in mills employing grinding rolls, for regulating the pressures of said rolls against the material being ground in a manner to achieve said advantages.

Other objects and advantages of my invention will become apparent from the following description of an illustrative embodiment thereof when taken in conjunction with the accompanying drawings, wherein:

Fig. 1 is an elevation of a bowl-type of roller mill with a portion of the casing broken away to show interiorly a typical roll and exteriorly that roll's associated improved spring means embodying the invention;

2

Figs. 2 and 3 are respectively side and front elevations of the improved spring means; and

Fig. 4 is chart showing the resultant spring pressures acting on the roller for various spring compressions when employing the invention.

Referring to Fig. 1, the roller mill, here shown by way of example as of the well known "Bowl" type, comprises a base 1 supporting a casing 2—2' thereabove within the lower portion 2 of which is 10 a bowl 3 mounted for rotation about a vertical shaft 4. The shaft 4 is supported in bearings (not shown) mounted within the base 1 and is rotated by a system of bevel gears (also not shown) within the base 1. Said gears are in turn 15 driven by a motor 5 through shaft 6.

The bowl 3 contains a peripheral grinding ring 7 onto which the material to be ground flows by centrifugal force from the inner portion of the rotating bowl. The material to be ground is supplied to the bowl downwardly from the mill top 20 through a central feed tube 8 from which it passes further downwardly from the upper casing portion 2' through opening 8 into the lower casing portion 2. The rotation of the bowl carries the material flowing onto the ring 7 to the rolls 9 where it is ground in passing between the rolls 9 and the ring 7.

An air current flows in well known manner upwardly between the rim of bowl 3 and the surrounding casing 2 and carries the sufficiently ground material up through the mill, as shown by the arrows, and out through the top off-take K. The insufficiently ground material is separated out of the air stream by the represented classifier Q and falls back into the bowl through opening 8' to be further ground.

The particular bowl mill here shown is equipped with three rolls 9 (only two can be seen in Fig. 1). Each roll 9 is mounted to freely rotate about the lower end of a shaft 10 which shaft is fastened at its upper end to an arm 11. Arm 11 is mounted to freely rotate on trunnions 12 which are carried in bearings 13, one of which is shown in cross section, mounted on the cover 14 of casing 2. Arm 11 extends radially outwardly 45 of the mill and terminates in a head 15 beyond the outer edge of cover 14, against the bottom of which head 15 the upper end of the main pressure spring 16 bears.

As shown in detail in Figs. 2 and 3, the means for supporting the main pressure spring 16 comprises the members 17 extending radially from the cover 14 on either side of the spring, each of which is slotted to receive one of the two vertical bolts 18 which are fully threaded and fastened 55 to the members 17 by top and bottom nuts 19. A

yoke 20 straddles the bolts 18 at their lower ends, is supported by nuts 25 on said bolts, and forms a spring seat 21 against which the lower end of the main pressure spring 16 bears.

Fastened to the bolts 18 above the members 17 by nuts 22, is a cross bar or stop 23 which serves to stop the upward movement of the head 15 of arm 11. A round rod 24 (see Figs. 2-3) is fastened to the top side of head 15 to form the contact with cross bar 23. If the main spring 16 is compressed, then by raising or lowering the cross bar 23 along bolts 18 by adjustment of nuts 22, the arm head 15 will be raised or lowered and the roll 9 will respectively be brought nearer to or farther from the grinding ring 7.

In this manner the gap between roller 9 and ring 7 may be varied. By raising or lowering the bottom yoke 20 along bolts 18 through adjustment of nuts 25, the compression of the main spring 16 may be increased or decreased and therewith the pressure against the head 15 of arm 11 and consequently the pressure on the material being ground between the roll 9 and the grinding ring 7.

The control of the gap between roll 9 and ring 7 and the pressure exerted by the main spring 16 on the material passing therethrough as described above, has heretofore been in common use.

According to this invention I provide a relief spring 26 which is seated at its upper end in a yoke 27 fastened to bolts 18 by nuts 28. The lower end of the relief spring 26 seats on a member 29 having plunger 30 which passes freely through a bore in the cross bar 23 and rests on the rod 24 of the head 15 of arm 11. A shoulder 31 on member 29, at the upper end of plunger 30, serves as a stop for its downward movement when it strikes the top of the cross bar 23.

By varying the gap 32 between the shoulder 31 and the cross bar 23, as by the insertion of shims 34, the movement of relief spring 26 may be limited. The compression relief spring 26 may be varied by the adjustment of the nuts 28 of yoke 27 along the bolts 18.

In operation, instead of depending upon the compression of main spring 16 alone for exerting the pressure on the roll 9, as was done heretofore, I now can controllably lower said pressure for a predetermined movement of the upper end of spring 16 by the opposing action of the relief spring 26 on the head 15 of arm 11. The new and advantageous results in mill performance which are attained by said combined action of the main and relief springs are discussed below.

Referring to Fig. 4, A represents the initial compression of the main spring 16 along line OA, and a that of the relief spring 26 along line Oa. The resultant pressure against the head 15 of arm 11 is A-a, which is also the pressure against the cross bar 23 when there is no material passing under the roll 9. The roll 9 is usually spaced from the grinding ring 7 so that in the absence of material therebetween, the cross bar 23 receives this resultant pressure of the springs.

When material is being ground between roll 9 and ring 7, the roll will depart further from the ring so that main spring 16 may be compressed to B or to C or to D or to E while the relief spring 26 will expand respectively to b or to c or to d or to o. The respective resultant pressures against head 15 of arm 11 are B-b or C-c or D-d or E; and in Fig. 4 these are plotted in line with the corresponding positions A, B, C, D, E of the upper

end of main spring 16, which also represent the downward movements of head 15 of arm 11.

The "Resultant" line has a much flatter slope than the line AE representing the main spring 16 and therefore the combined spring action provides greater pressure variations than the single main spring used heretofore, for the same movement.

These greater pressure variations are of especial advantage when grinding different grades of coals. For low grindability coals a relatively high roll pressure is desirable while for high grindability coals about half of said pressure is desirable with a closer gap between roll and ring. These conditions are satisfactorily met by the combined springs 16 and 26 as uniquely organized by me, but not by the single spring 16 used heretofore. The new arrangement will then permit grinding various grades of coals without adjusting spring pressures.

Furthermore, it is desirable to have the pressure build up rapidly as the material in the mill bowl 3 accumulates so as to get quick response to changes in load, for example, when the mill 25 is used for firing steam boilers in power plants; and my new double spring arrangement effectively provides for this.

Also because of the lower spring pressures when the roll 9 is near the ring 7, it will nip 30 the coal with a rolling action instead of tending to plow it aside as is the case when the pressures are higher.

Another advantage of these lower spring pressures lies in a quieter running mill over a wide 35 range of capacities. With a light pressure on the roll 9, there is a minimum of noise and vibration when that roll is near the grinding ring 7; and this is of especial advantage since under the conditions stated there is no thick cushion of material to absorb noise or vibration.

Although the combined springs 16 and 26 provide the advantage of greater pressure variations for the same movement than are obtained by the single main spring 16 as used heretofore, it would be possible to substitute a single, much 45 heavier spring which would compress along the "Resultant" line of Fig. 4. However the use of such a heavy spring becomes objectionable when the gap between the roll and ring is materially increased by the passage therethrough of foreign matter, such as tramp iron. The resulting high compression of such a heavy spring would then cause a prohibitive pressure on the roll and arm 11. But when using the opposing springs, according to my invention, the gap 32 between the shoulder 31 of member 29, and the cross bar 23 may be limited so that beyond the normal movement of the head 15 of arm 11, shoulder 31 will seat on cross bar 23 and limit the action of relief spring 26. Thereafter the main spring 16 alone will act upon head 15 of arm 11 and the rate of pressure increase will be reduced.

Referring to Fig. 4, if the gap 32 is set to close at B-b, or at C-c, or at D-d, the pressures will 65 rise from there to B, or to C, or to D respectively (along the dashed lines), and thence increase along line AE representing the compression of the main spring. Obviously many variations in choice of springs and in their opposing pressures may be made.

While I have here disclosed my invention as being applied to a bowl-type mill having rolls 9 urged towards a grinding ring 7 carried by a rotatable bowl 3, it will be apparent that such disclosure is illustrative rather than restrictive

and that my inventive improvements may with comparable benefit also be applied to mills of other types, such as those using rollers or balls running adjacent tables or races, wherein the problem solved by this invention is encountered.

Moreover, even though only one illustrative embodiment has been shown and described, it will be understood that changes in construction, combination and arrangement of parts may be made without departing from the spirit and scope of the invention as claimed.

I claim:

1. In a roller mill having a casing and a rotating bowl therein including a grinding ring, a roll mounted in the casing arranged to roll on and grind material between the roll and ring, shaft means on which said roll is mounted for rotation thereon, a trunnion bearing mounting said shaft means on said casing about which trunnion said roll may be moved toward and away from said ring, a main spring arranged to act at its one end on a portion of said shaft means to urge said roll toward said ring, a stop bar engaging said portion to limit the movement of said shaft means and therewith the movement of said roll toward said ring, at least one bolt mounted on said casing and nuts on said bolt adjustably supporting said stop bar longitudinally of said bolt, a relief spring arranged to act at its one end on said portion of said shaft means to oppose said main spring and tending to urge said roll away from said ring, a member interposed between said relief spring and said portion of said shaft means having a plunger, means forming a bore in said stop bar through which said plunger freely moves to act on said portion, adjustable means mounted on said stop bar engaging said member to limit the action of said relief spring, and a crossbar adjustably supported by nuts longitudinally of said bolt and bearing against the other ends of each of said main and relief springs to individually vary the pressure exerted by either of said springs on said portion and said roll and thereby on said material.

2. In a roller mill having a casing and a rotating bowl therein provided with a grinding surface, a roll mounted in the casing arranged to roll on and grind material between the roll and grinding surface, a shaft adjacent one end of which said roll is mounted for rotation thereon, an arm extending from said shaft adjacent the other end thereof and fastened thereto, a pin on said arm adjacent said shaft journaled on said casing to rotate said arm and therewith said shaft and roll to move said roll toward and away from said grinding surface, a head on said arm at its extended end for receiving one end of a main spring, said main spring acting to urge said roll toward said grinding surface, means for adjusting said spring to vary the pressure against said

60

head, a stop bar mounted on the casing to limit the movement of said head and therewith the movement of said roll toward said grinding surface, means adjusting the position of said stop bar with respect to said arm head and therewith the gap between said roll and said grinding surface, a relief spring acting on said arm head in direction opposite to said main spring, means for adjusting said spring to vary the pressure against said head, and means on said bar to adjustably limit the action of said relief spring.

3. In a roller mill having a casing and a rotating bowl therein including a grinding ring, a roll mounted in the casing arranged to roll on and grind material between the roll and ring, a shaft adjacent one end of which said roll is mounted for rotation thereon, an arm extending from said shaft adjacent the other end thereof and fastened thereto, a pin on said arm adjacent said shaft journaled on said casing to rotate said arm and therewith said shaft and roll to move said roll toward and away from said ring, a head on said arm at its extended end for receiving one end of a main spring, said main spring acting at one end to urge said roll toward said ring, a bar engaging said head to limit the movement thereof and therewith the movement of said roll toward said ring, bolts mounted on said casing and nuts on said bolts adjustably supporting said stop bar longitudinally of said bolts, a relief spring acting at one end on said arm head in direction opposite to said main spring, a member having a plunger interposed between said relief spring and said arm head, means forming a bore in said stop bar through which said plunger freely moves to act on said arm head, shims mounted on said stop bar engaging said member to variably limit the action of said relief spring, and a crossbar adjustably supported by nuts longitudinally of said bolts and bearing against the other ends of each of said main and relief springs to individually vary the pressure exerted by either of said springs on said arm head and said roll and thereby on said material.
